(57) CLAIM

The ornamental design for a bathroom container, as shown and described.

DESCRIPTION

FIG. 1 is a front-left perspective view of the bathroom container;

FIG. 2 is a back-left perspective view;

FIG. 3 is a right side view;

FIG. 4 is a front view;

FIG. 5 is a left-side view;

FIG. 6 is a top view;

FIG. 7 is a bottom view; and,

FIG. 8 is a back view thereof.

The broken lines showing bottom elements of the bathroom container are for the purpose of illustration and form no part of the claimed design.
